UNITED STATES PATENT OFFICE.

EUSTACE OXLEY, OF BROOKLYN, NEW YORK, ASSIGNOR TO THE GENERAL ELECTRIC COMPANY, A CORPORATION OF NEW YORK.

CONTROLLING ARC-LAMPS.

SPECIFICATION forming part of Letters Patent No. 697,007, dated April 8, 1902.

Application filed August 25, 1900. Serial No. 28,006. (No model.)

To all whom it may concern:

Be it known that I, EUSTACE OXLEY, a subject of the Queen of Great Britain and Ireland, residing at Brooklyn, in the State of New York, have invented certain new and useful Improvements in Controlling Arc-Lamps, (Case No. 1,223,) of which the following is a specification.

In lighting by arc-lamps it is frequently desirable to operate some of the arc-lamps in the distribution-circuit for determinate periods only, and in cases where such a use is practicable the consumer desires a charge rate less than that made by the supply company for an unlimited service. For example, a merchant may desire the use of certain arc-lamps in his store or other place of business only for a few hours in the evening, or sometimes constant-potential lamps are supplied from a low-tension mixed distribution system for street-lighting, and it is necessary to burn the arc-lamps only at certain hours, and in such systems it is sometimes greatly to the advantage of the supply company to furnish current for arc-lamps of this type, since they may burn at a time when there is a dip in the load curve, and the efficiency of the system may therefore be increased. Methods have been proposed for controlling the operation of arc-lamps for such purposes. In some extra conductors are employed to cut in and out the lamps at specified times; but a serious objection to this is the additional conductor or conductors required, increasing both the expense of installation and the liability of the system to get out of order. Others employ eight-day clocks to govern the lamp-switches. This is also expensive and liable to be uncertain. I have provided an organization by which the same results may be accomplished without the employment of extra conductors and which will permit the control of the lamps from the central station or other desired point in the system. I effect this result by electromagnetically controlling the lamps over a circuit formed of the supply-wires themselves, the operation of a controlling device at the central station or other point of control being all that is needed to insure the kindling or extinguishment of the

lamps. In a three-wire distributing system the result may conveniently be effected by providing a switch at the central station by which one of the potential-wires may be grounded, a grounded electromagnet at the point where the lamps are employed being thereby put into circuit and acting to cut in the lamp. In a two-wire system the organization would be exactly the same.

The invention also embodies various features, the novelty of which will be hereinafter pointed out and which will be definitely indicated in the appended claims.

In the accompanying drawings, which illustrate diagrammatically a system embodying my improvements, Figure 1 shows the application to a three-wire low-potential direct-current system, and Fig. 2 to a two-wire system, such as that employed in the operation of electric railways where the return-circuit is insulated.

1, 2, and 3 in Fig. 1 represent the three wires of a direct-current-supply system, which may be employed to operate the usual mixed types of translating devices supplied with energy from such circuits. These may be motors, incandescent electric lamps, inclosed-arc lamps, and other types of electric apparatus.

4 represents a constant-potential arc-lamp, the circuit of which may be controlled by a switch actuated by an electromagnet 5, connected in a ground branch 6, leading from one of the wires, say, to the neutral wire 2 of the distributing system. The switch may be of any satisfactory construction, but should be organized so that with continuous operation the circuit may at any time be opened and closed with certainty by the operation of the controlling-switch at the central station. I have shown in the drawings a revolving type of switch, in which a drum or disk is provided at equal circumferential positions with strips of insulation embedded in its rim, the contact-spring 7 being set so as to bear upon the periphery. The axis upon which the disk is mounted carries a fixed ratchet-wheel 8, which is engaged by a pawl carried by the lever on which the armature of the electromagnet 5 is mounted. A spring or other retractile agent and a set-screw or back-stop, as indicated in

Fig. 1, are provided to limit the movement of the armature. In conductive relation to the metallic disk is an elastic contact 9, bearing on its shaft a contact which connects with one 5 terminal of the lamp. The other terminal of the lamp and the brush 7 lead to two mains of different potential, as 2 and 3. At the central station I provide a switch 10, the pivot of which is grounded, as by the wire 11, and which 10 may be brought into engagement with the contact 12, connecting with one of the potential wires of the system. Thus when the switch is closed one of the wires, as 3, is grounded, permitting current to flow through the ground 15 6 at the several translating devices which are to be selectively controlled and through the switch-operating electromagnet 5 to the neutral wire 2, thus operating the electromagnet and impelling the switch-disk forward, so as 20 to bring one of the bare spots into engagement with the brush 7, a condition exemplified in Fig. 1 of the drawings, in which case the lamp derives current from the system by way of one of the potential wires, as 3, brush 7, conducting-disk, brush 9, wire 13 through the lamp-circuit to the neutral wire 2. Of course where a 25 number of such lamps are controlled they may be apportioned on the sides of the three-wire circuit shown in Fig. 1 in such a way 30 as to balance the load between the two generators, a similar grounding-switch being provided for the other main. After closing the switch 10, and thus effecting the cutting in of the lamp, it should be opened again, so as 35 to disconnect the ground, and when the time arrives for cutting out the lamp the operator at the central station may again close the switch, thereby giving the switch-disk that controls the lamp another forward impulse, 40 causing the brush to come into engagement with one of the insulating-spots, and thereby cutting out the lamp. Thus it will be seen that repeated control of the lamps may be effected without interfering with the proper action of the switch. It is not imperative, however, that a switch of the particular type 45 shown should be employed, since the only essential requirement is that the electromagnet 5 may be energized and then after per- 50 forming work be deenergized without cutting out the lamp, to the end that the lamp may operate for a desired period and that when the electromagnet is subsequently energized it may rupture the lamp-circuit.

55 To the end that the operator at the central station may know the condition of adjustment of the translating devices he is controlling, I provide at the central station an indicator showing when they are operating. A 60 convenient way of controlling the indicator is by the employment of a switch similar in construction to that employed in controlling the translating devices, an indicator being included in place of the translating device— 65 such, for example, as an incandescent lamp. 14 represents such an indicator, and 15 a

switch-disk for controlling it in a manner similar to that already described at the consumer's station. When the switch is closed, it will be seen that the electromagnet 5^a is 70 put between the potential-wire 3 and the neutral wire, thus operating its armature and shifting the switch-disk simultaneously with the switch-disk at the consumer's station, the lamp 14 being thereby cut in between the mains 2 and 3 and burning until the switch 10 is again closed. Thus the indicator 14 serves to prevent poor service by preventing mistakes on the part of the operator in forgetting to operate the switch or in operating 80 it more than once.

My improvements are equally applicable to two-wire distribution-circuits, since it will be perfectly evident from an examination of Fig. 1 that the omission of the wire 1 will in no 85 sense alter the method of control.

In power-circuits, such as are employed for operating electric railways, and particularly where the return-circuit is insulated, it may also be applied. Such an organization is 90 shown in Fig. 2, where a railway-circuit, such as a five-hundred-volt underrunning trolley system, is illustrated. In such circuits it is common to employ a group of arc-lamps connected in series, five commonly being inserted 95 across the circuit, as indicated at 16. The mode of control is exactly the same as that described in connection with Fig. 1, corresponding parts having the same numbers. It will therefore be unnecessary to repeat the 100 description.

While I have shown and described a specific method of operating the controlling-switch, my invention is not limited thereto, but may be carried out in other ways in which 105 the current-carrying wires of the system are employed to selectively operate the translating devices; nor is my invention limited to the mode of control herein specifically described, as other ways of imposing operating 110 current or potential on the switches governing the operation of the translating devices may be employed with the broader claims hereinbelow set forth.

Having thus described my invention, what 115 I claim as new, and desire to secure by Letters Patent of the United States, is—

1. In a system of electrical distribution, the combination, with a supply-circuit, of a plurality of translating devices in operative relation thereto, a magnetically-operated circuit-controller in a ground branch of the supply-circuit, controlling the several translating devices, a switch operated by said circuit-controller to cut in and out the several translating devices, a second ground branch of opposite electrical potential at the control-station, and a switch for opening and closing said branch.

2. In a system of electrical distribution, the 130 combination with a supply-circuit, of a plurality of translating devices in operative re-

lation thereto, a magnetically-operated circuit-controller in a ground branch of the supply-circuit for the respective translating devices, a switch operated thereby to cut in and 5 out of circuit the respective translating devices, a second ground branch of opposite electrical potential at the control-station governing the circuit-controller, a switch govern-

ing said branch, and an electric indicator in the control-circuit at the control-station. 10

In witness whereof I have hereunto set my hand this 23d day of August, A. D. 1900.

EUSTACE OXLEY.
